UNITED STATES PATENT OFFICE.

HENRY R. AUTH, OF TOLEDO, OHIO.

DESIGN FOR A BOLSTER FOR TOY WAGONS.

SPECIFICATION forming part of Design No. 32,256, dated February 20, 1900.

Application filed August 14, 1899. Serial No. 727,215. Term of patent 14 years.

To all whom it may concern:

Be it known that I, HENRY R. AUTH, a citizen of the United States, residing at Toledo, Lucas county, Ohio, have invented and produced a new and original Design for Bolsters for Toy Wagons, of which the following is a specification, reference being had to the accompanying drawing, forming part hereof.

As shown in the drawing, the leading or material feature of my design consists of a bolster for toy wagons in which by the employment of a single integral piece the spindles or axle are secured in place, clips are provided for the tongue of the wagon, and said clips are braced from the bolster.

The axle-piece *a* is in the form of a mutilated tube from each end of which project the spindles or axle for the wheels of a wagon. Formed integral with the tube and projecting forwardly at right angles therewith are parallel clips or plates *c c*, designed to receive between them and to engage the rear

end of the tongue of the wagon. Through these braces are coincident horizontal holes designed to receive a pin for pivotally securing the tongue in place between the two clips. Braces *d d* lead from the axle-piece near each end thereof forwardly and inwardly to the plates or clips *c c*. The tubular piece *a* midway of its length is flattened into a disk-like 25 plate, as at *e*, and through this flattened portion is a circular opening *f*. This opening is designed to engage at its margin with a "spider" or tripod for the support of the wagon-bed. 30

Having described my invention, what I claim, and desire to secure by Letters Patent, is—

The design for a bolster for toy wagons as herein shown and described.

HENRY R. AUTH.

In presence of—

F. M. DOTSON,
L. E. BROWN.
